UNITED STATES PATENT OFFICE.

OTTO PETERMANN, OF NEW YORK, N. Y., ASSIGNOR, BY MESNE ASSIGNMENTS, TO CORONA TYPEWRITER COMPANY, INCORPORATED, A CORPORATION OF NEW YORK.

LINE-SPACING MECHANISM FOR TYPE-WRITING MACHINES.

1,121,031.

Specification of Letters Patent.

Patented Dec. 15, 1914.

Application filed June 12, 1909. Serial No. 501,851.

To all whom it may concern:

Be it known that I, OTTO PETERMANN, a citizen of the Republic of Switzerland, and a resident of New York, county and State 5 of New York, have invented certain new and useful Improvements in Line-Spacing Mechanism for Type-Writing Machines, of which the following is a full, clear, and exact description.

10 This invention relates more particularly to line spacing mechanism of foldable front strike or visible typewriting machines.

The primary object of the invention is to provide simple and efficient mechanism 15 for typewriting machines which will positively move the platen to different distances to space the same for one or more lines, and to provide means which will properly hold the platen when moved so that the spacing 20 between all of the lines will be equal.

Other objects of the invention are to provide simple means whereby substantially the entire surface of the platen may be utilized; and to provide simple means serving 25 as a stop and lock for the platen when moved.

A further object of the invention is to provide simple and efficient means for releasing the platen so that the same may be 30 manually and freely moved in either direction.

With these and other objects in view, the invention will be hereinafter more particularly described with reference to the 35 accompanying drawings, which form a part of this specification, and will then be pointed out in the claims at the end of the description.

In the drawings, Figure 1 is a side elevation of one form of machine embodying 40 my invention. Fig. 2 is an enlarged transverse section through the carrier taken on the line II—II of Fig. 3. Fig. 3 is a fragmentary sectional view, showing the stop 45 for the line-spacing mechanism which may be frictionally held to the frame in different positions. Fig. 4 is a plan view of the carrier and platen detached, showing the line-spacing mechanism; and Fig. 5 is 50 a fragmentary rear elevation of one end of the platen and carriage.

The machine shown and hereinafter set forth is of the type disclosed in the patent to Frank S. Rose, No. 754,242, patented 55 March 8th, 1904, in which the carriage is

adapted to be folded over above the keys, and while in the present invention the carriage and platen and their operating mechanism are adapted to be raised and lowered on the frame of the machine and to be folded over above the keyboard, and in which the type have a front strike for visible writing, it is to be understood that the features of this invention may be used in connection with other classes of machines.

The frame 10 may be of any suitable construction, and mounted above the frame 10 is a support 11, which is adapted to be moved vertically to permit the type-heads to have a plurality of characters thereon, and said support is pivotally held so as to adapt the same to be folded over above the keyboard.

A carriage 12 is held to move upon the support 11, and this carriage has suitable 75 mechanism for operating the same and is provided with a frame 13 in which a platen 14 is held to rotate, the said parts thus far referred to, as well as the ribbon mechanism and other parts not shown, being of any desired construction.

As a means for operating the platen for line-spacing to move the same various distances and for preventing the platen from having too great a movement, a ratchet 85 wheel 15 is held to move with the platen, said platen having the usual hand-operating means or disks 16 located at the opposite ends of the shaft 17 to adapt the platen to be rotated independently of the line-spacing 90 mechanism. The carriage frame is provided with an outwardly-extending fixed gripping or finger part 18 from which projects brackets or lugs 19 and 20. A lever 21 is pivotally held to the brackets 19 and 95 20 and said lever has an upwardly-extending part 22 serving as a finger portion therefor, said lever being opposed to the fixed gripping part 18 and having a pivotal movement in the direction of travel of 100 the carriage. A bolt 23 extends transversely through the brackets 19 and 20 above the platen shaft 17 and is fixed to said brackets, and said bolt serves as a pivot for the lever 21. The lever 21 has an arm 24 105 located adjacent to the bracket 19 and normally abuts against the inner side of said bracket to permit the lever to slide or move laterally of the platen and lengthwise of the bolt 23, and arranged around said bolt 23 110

is a spring 25 one end of which abuts against the arm or part 24 of the lever 21 and the bracket 20 and tends normally to hold said lever in the position shown in Fig. 4. This lever 21 has an arm 26 which is somewhat longer than the arm 24 and through which the bolt 23 also passes, and said arm is located on the outside of the bracket 20 to permit the lever to have a movement lengthwise of the bolt 23. The arm 26 has an engaging end forming a fixed tooth or pawl 27 so that when the lever 21 is forced toward the fixed part 18 of the carriage frame by grasping the finger parts, the said lever 21 will have a lateral and downward movement and will engage the teeth of the ratchet wheel 15 to rotate the platen and the work sheet carried thereby, at the same time permitting the carriage to be moved toward the starting point against the action of the usual power mechanism.

A stop or lever 28 is pivoted to the carriage on the outside thereof and is provided with a plurality of notches or abutments 29 and 30. The lever 21 in its downward movement will strike either of the notches 29 and 30 of the stop lever 28 to limit the movement of said lever 21. If the stop lever 28 is moved to a position to cause the lever 21 to engage the notch 30, the platen will be rotated a certain distance only, and if said lever 28 is moved so that the notch 29 is engaged by the lever 21 the platen will be given a greater throw, thus varying the movement of the platen for line spacing. By reason of the nature of the notches or engaging parts of the stop lever 28 and the engaging part or arm 26 of the lever 21, the platen will be positively locked and prevented from moving more than it should when operated rapidly; said locking lever 28 being provided with a depressed or other part 31 which engages recesses 32 in the carriage frame and holds said lever 28 in either position.

The teeth of the platen ratchet wheel 15 are engaged by a roll 33, and this roll is carried by a pivoted lever, arm or member 34, Fig. 2, which is normally forced in one direction by a spring 35. The upper end 36 of the lever is substantially U-shaped and is adapted to be engaged by the arm 37 of a pivoted lever or member 38 so as to hold the roll out of engagement with the ratchet wheel 15 when it is desired to rotate the platen independently. The teeth of the ratchet wheel 15 are large enough to be engaged by the pawl or dog 27 and still are small enough to permit the platen to be shifted independently of its operating mechanism and be again engaged by the pawl to bring a new part of the platen in position for the type to strike against in order that substantially the entire surface of the platen may be utilized.

From the foregoing it will be seen that simple and efficient means are provided for moving the platen for line spacing and for locking the same; that said mechanism may be quickly operated to adapt the platen to be moved one or more spaces at a time; and that simple means are provided whereby the platen may be released to adapt the same to be moved freely and manually in either direction.

Having thus described my invention, I claim as new and desire to secure by Letters Patent:

1. In a typewriting machine, the combination with a rotary platen provided with a toothed wheel, of a manually operating pivoted lever having a fixed pawl adapted to engage said toothed wheel and rotate the platen, said lever having a bodily movement sidewise of its pivotal movement, and means for adjusting the throw of said pawl to regulate the movement of the platen.

2. In a typewriting machine, the combination of a carriage, a platen mounted thereon, a ratchet wheel held to move with the platen, and a pawl-carrying finger lever having a pivotal movement in the direction of travel of the carriage and a bodily movement transversely thereof and adapted to engage the ratchet wheel and rotate the platen.

3. In a typewriting machine, the combination of a carriage, a platen mounted thereon, a finger lever carrying a pawl and having a pivotal movement in the direction of travel of the carriage and a sliding bodily movement transversely thereof and in a rearward direction, a ratchet wheel held to move with the platen and adapted to be engaged by the pawl, and a movable stop adapted to engage a part of the lever to regulate the movement of said platen.

4. In a typewriting machine, the combination with a rotary platen provided with a toothed wheel, of a manually operated pivoted lever carrying a pawl and having a bodily movement sidewise and along its pivoting means and adapted to engage said toothed wheel to adjust the platen, and a locking lever having abutments adapted to be moved into position in the path of movement of said lever to regulate its throw in connection with the toothed wheel for line spacing.

5. In a typewriting machine, the combination of a carriage, a platen mounted thereon, a supporting shaft for said platen, a ratchet wheel held to move with the platen, and a pivoted finger lever mounted independently of the platen shaft and having a bodily movement sidewise of its pivotal movement for operating said ratchet wheel and rotating the platen.

6. In a typewriting machine, the combination of a carriage, a platen mounted thereon, a supporting shaft for said platen, a ratchet wheel held to move with the platen, and a

finger lever pivotally mounted at one side of the platen shaft and having a bodily movement sidewise of its pivotal movement and carrying a pawl to engage said ratchet wheel and rotate the platen.

5 7. In a typewriting machine the combination of a carriage, a platen mounted thereon, a supporting shaft for the platen, a ratchet wheel held to move with the platen, and a finger lever pivotally mounted at one side of the platen shaft and having a swinging movement and a bodily sliding movement sidewise of its swinging movement to adapt the lever to move toward and around the 10 ratchet wheel, and a pawl adapted to engage said ratchet wheel and rotate the platen.

15 8. In a typewriting machine, the combination with a carriage having a finger part fixedly mounted thereon, of a rotary platen 20 provided with a toothed wheel, a manually operated lever carrying a pawl and provided with a finger part and adapted to engage said toothed wheel and rotate the platen, and a lever for adjusting the throw 25 of said pawl to regulate the movement of the platen.

9. In a typewriting machine, the combination with a movable carriage provided with recesses, of a platen mounted thereon, a 30 ratchet wheel held to the platen, a pivotally mounted lever carrying a pawl adapted to engage the ratchet wheel and having a movement sidewise of its pivotal movement, a pivotally held lever stop having abutments 35 adapted to vary the throw of the lever according to the position of said stop, and provided with a depressed portion adapted to engage the recesses in the carriage.

10. In a typewriting machine, the combination of a carriage, a platen mounted thereon, a ratchet wheel held to move with the platen, a fixed gripping part extending upwardly at one end of the carriage, a manually operated and pivoted lever in line with 45 and directly opposed to the fixed gripping part and a pawl carried by the lever adapted to engage the ratchet wheel for imparting a rotary movement to the platen.

11. In a typewriting machine, the combination of a support, a carriage adapted to travel along said support, a platen mounted on the carriage and provided with a shaft, a ratchet wheel held to move with the platen, a fixed gripping part, brackets extending 55 outwardly from said part, a bolt held to said brackets, a lever having a finger portion and provided with arms of relatively different lengths adapted to be pivotally and slidably held on said bolt, a spring arranged around 60 the bolt and having one end abutting against one of the brackets and the other end against one of the lever arms tending normally to force the lever in one direction, and a pawl carried by said lever adapted to engage the 65 teeth of the ratchet wheel to operate the

same and during such engagement have a rearward downward movement.

12. In a typewriting machine, the combination of a support, a carriage adapted to travel along said support, a platen mounted 70 on the carriage and provided with a shaft, a ratchet wheel held to move with the platen, a fixed gripping part, brackets extending outwardly from said part, a bolt held to said brackets, and a finger lever opposed to said fixed gripping part, said lever being pivotally and slidably held on said bolt and having means to engage the ratchet wheel and 75 rotate the platen.

13. In a typewriting machine, the combination of a support, a carriage adapted to travel along said support, a platen mounted on the carriage and provided with a shaft, a ratchet wheel held to move with the platen, a fixed gripping part extending upwardly 85 from one end of the carriage, brackets extending outwardly from the carriage, a bolt extending transversely of the platen and held to said brackets, a lever having a finger portion and provided with arms and pivotally 90 and slidably held on said bolt, means movable with the lever adapted to engage the ratchet wheel and rotate the platen, and means for limiting the movement of said lever.

14. In a typewriting machine, the combination of a support, a carriage adapted to travel along said support, a platen mounted on the carriage, a fixed gripping part extending upwardly from one end of the carriage, brackets extending outwardly from said part, a bolt extending transversely of the platen and held to said brackets, a lever having a finger portion and provided with arms of relatively different lengths and pivotally and slidably held on said bolt, a spring arranged around the bolt and having one end abutting against one of the brackets and the other end against one of the lever arms tending normally to force the lever in one 100 direction, means operated by the lever to rotate the platen, and means for limiting the movement of said lever.

15. In a typewriting machine, the combination of a support, a carriage adapted to 115 travel along said support, a platen mounted on the carriage, a ratchet wheel held to move with the platen, a bolt extending transversely of the platen and held to parts projecting outwardly from one end of the carriage, a movable lever having a finger portion and provided with arms of relatively different lengths adapted to be pivotally and slidably held on said bolt, a spring arranged around the bolt and having one end abutting 120 against one of the brackets and the other end against one of the lever arms tending normally to force the lever in one direction, and a pawl fixed to said lever adapted to engage the teeth of the ratchet wheel to 130

operate the same and during such engagement having a lateral and downward movement.

16. In a typewriting machine, the combination of a carriage, a platen mounted on the carriage, a ratchet wheel held to move with the platen, means for rotating the ratchet wheel and platen, a vertically arranged and pivoted arm having an open 10 U-shaped space at its upper end, a roll forming a detent held in said space and adapted to engage the teeth of the ratchet wheel, a spring normally forcing the arm in one

direction, and an independent pivotally held member having an arm adapted to enter the 15 space adjacent to the roll to release the same from engagement with the ratchet wheel to permit the platen to be manually operated freely in either direction.

This specification signed and witnessed 20 this 4th day of June A. D. 1909.

OTTO PETERMANN.
